UNITED STATES PATENT OFFICE.

GEORGE A. RAYMOND, OF WAUKEGAN, ILLINOIS.

WIRE-FENCE-WEAVING MACHINE.

1,119,728.

Specification of Letters Patent.

Patented Dec. 1, 1914.

Application filed April 10, 1913. Serial No. 760,265.

To all whom it may concern:

Be it known that I, GEORGE A. RAYMOND, a citizen of the United States, residing at Waukegan, in the county of Lake and State 5 of Illinois, have invented certain new and useful Improvements in Wire-Fence-Weaving Machines, of which the following description, taken in connection with the appended claims and accompanying drawings, 10 forms the specification.

The present invention relates to improvements in machines for weaving fence where- 15 in the strands comprise a series of two wires twisted together to form a cable and fluted or crimped cross bars or stays distributed between the strands at predetermined intervals during the process of weaving, to give the fence stability and keep the cables in spaced parallel arrangement, the twisting of 20 the cables being reversed between each set of cross bars.

The invention has, among other objects, to construct a machine of its class, whereby the fencing cables may be spaced at various 25 widths to accommodate the requirements of the weaver; whereby the cross stays may be regulated in length to accommodate either wide or narrow fencing; whereby the crimping of the cross stays may be varied; whereby 30 the cross stays may be varied in their spacing; whereby the cross-stays may be firmly seated between the strands of the cables; whereby the fencing reel or spool will afford better facility for removing the fencing; and whereby the machine will be 35 comparatively simple in construction, automatic and positive in action, economical in upkeep, and convenient to adjust and regulate.

The invention, stated generally, consists 40 in improvements in the construction of the various elements, and in the combination of devices by which the machine is adapted to accomplish the results hereinbefore enumerated and hereinafter more fully set forth.

In the drawings forming a part of this 45 specification, Figure 1 is an end elevation embodying my invention, and shows the operative mechanism in the position it occupies antecedent to thrusting a cross bar or stay between the fencing strands, the inter- 50 mittently-acting cable twisting gear being idle in this position. Fig. 2 is a plan view in a like position with the crimping and take-up rolls partially broken away to show the 55 cable twisting apparatus more clearly. Fig.

3 is an enlarged side elevation in a like position looking into the machine, and taken on a section along the line $x-x$ of Fig. 2. Fig. 4 is a like elevation with the operative parts in changed positions. Fig. 5 is a detail side 60 view of the cross-stay crimping mechanism. Fig. 6 is a front elevation of the same. Fig. 7 is a detail section of a cable twister and cross stay guard in normal position but partially broken away. Fig. 8 is a plan view of 65 the same. Fig. 9 is a detail perspective view of the twister gear. Fig. 10 is a detail view, partially in section, of the measuring reel and take-up anti-backlash ratchet and shaft, and a ratchet for operating the same. Fig. 70 11 is a side elevation of the same with a portion of the operating ratchet broken away. Fig. 12 is a detail side elevation of the anti-backlash ratchet with its end removed, the arrow indicating the operative movement of 75 the same. Fig. 13 is a detail section of the fencing reel operating mechanism and its bearing at the operating end. Fig. 14 is a detail side elevation of the bearing.

Like marks of reference refer to corresponding parts throughout the different views, in which—

A and B represent the side frames, C the cross frame, D a drive belt pulley, E, F and G a series of reducing gears, H the main 85 driving gear.

Mounted within suitable bearings upon the cross frame C are two transverse shafts 1 and 2, the former being fitted at one end with the drive gear H and at the opposite end with a gear 3 provided with teeth about one-half of its circumference, the other with a correspondingly-sized intermeshing intermittent gear 5 arranged to operate one revolution to the driving gear twice; the 95 gear 3 being made in any customary or convenient manner to obtain the desired result. Forward of and above these gears, and journaled within suitable bearings on the frame ends, the measuring and crimping rolls I 100 and J are fitted, the same being driven in unison by the gears 6 and 7, and that the roll I may be adjusted to and from the roll J to vary the crimp of the fence as the occasion may require, its bearings 8 are slidably adjustable on the frame ends, said adjustment being arranged in any customary and convenient manner. Below and at the side of the machine opposite the gears 3 and 5 the fence reel or spool K is journaled. This reel 105 110

- at the free end of its shaft is journaled in a loosely fitting open sided box, (not shown), in the frame A and is retained by a vertical pin 9 and near its opposite or driven end is 5 journaled in a gimbal bearing 10 for the purpose of affording quick and easy access to swing the free end of the reel from the open sided box to release the fencing from the reel without molesting its driving chain.
- 10 The dotted lines in Fig. 2 represent the reel swung clear of the machine at its free end to afford easy access to the reel, as aforesaid.
- The shaft 11' of the reel K is directly 15 driven from the shaft 11 and the roll J through the medium of a sprocket chain 12 trained over sprocket gears 13 and 14 of the respective shafts, and the measuring and crimping roll is actuated by a ratchet and 20 pawl 14' and 15 respectively operative at the end of its shaft, as shown, the pawl lever 16 in turn being reciprocated by a connecting rod 17 engaging with a sway-bar or lever 18 pivoted at the inner end 19 25 to the frame end A near the bottom thereof, the bar, near its engagement with the connecting rod extending from the machine through an aperture, (not shown), in the end B thereof.
- 30 Inasmuch as the fence reel K and the measuring and crimping roll J are actuated simultaneously and their shafts at the same speed, it is obvious that the fencing would increase in bulk as it became wound on the reel, and a variation in speed of the roll and reel would naturally result. To accommodate this variation the sprocket 13 of the reel is permitted to slip on its shaft, and to provide for this variation the sprocket 40 is formed with a smooth central portion and fitted between friction surfaces such as indurated fiber, leather or equivalent disks 20, and these in turn fitted between clamping disks 21 and 22, the latter being firmly attached to the shaft and the former being held in position by means of a nut 23 run on the threaded end of the shaft and adjusted thereby to suit the demand required. That the crimping and measuring roll J 45 may be regulated to accommodate the taking up of fence being woven, such as variations arising in the spacing of cross stays, the ratchet lever 16 is provided with spaced apertures 16' by which the connecting rod 17 may be adjusted in its attachment, adjusting the connections toward the ratchet increasing the throw of the roll, and adjusting the connections outward from the ratchet diminishing the throw of the roll. 50 That the measuring roll shall not react from the strain of fencing drawn up through the twisters, (the latter of which will be herein-after more fully described), a roller ratchet 24 is fitted to the shaft of the same and held 55 in place by a pin 25 passing through the

parts. The inclination of the peripheral pockets 26 of this ratchet is such that the rollers 27 carried therein will engage the outer cage 28, which is rigidly attached to the frame B, and permit the measuring roll 70 to draw up on the fence, (a direction indicated by the arrow in Fig. 12), but prevent its recoil or backlash. A cover 28' is fitted over the open end of said cage to retain said rollers, as shown in Figs. 1, 2 and 10. 75

Crossing the machine from end to end and transverse of the gears 3 and 5 is a rock shaft 30 and a rigidly fitted round bar 30', the former being fitted above and somewhat back of the latter. Upon the bar 30', the 80 cross bar or stay wire cutter bracket 31 and wire twister brackets 32 are adjustably fitted, and on the rock shaft 30 the cross bar guide holders 33 are adjustably fitted, both the brackets and holders being secured 85 by set screws 34. The wire twisting or cable forming mechanism comprises a reduced central portion 35 and oppositely-disposed bearing portions 36, the lower portion adjoining a gear 37 diametrically larger than 90 said bearing and having a hub with an enlarged terminal rim 38 provided with oppositely-disposed grooves 39, the opposite end of the mechanism terminating in an elongated reduced hub 40, wire-conducting 95 holes 41 alined with the grooves in said rim and opening through both the gear and the bearings aforesaid. The brackets 32 are bored to receive the bearings 36 of the wire twisters which are received in a vertical 100 position with the gear underneath, as shown, and to secure the twisters within the respective brackets, thimbles 42 are fitted over the reduced upper terminals of the same and fastened by means of a pin 43 105 passing through the parts, a spacing and friction ring 44 being fitted between each thimble and its bracket. The thimbles at their free ends are bored in alinement with the wire apertures in their respective twisters, and to prevent undue wear may be hardened as expedient. 110

Crossing the frame from end to end and received by forwardly-depending portions 45 of the twister brackets, the twister-actuating rack 46 is held in engagement with the gears of the respective twisters. The free end of this rack passes through an aperture in the frame A and its opposite end is fitted to a cross head 47 working in ways 115 48, the latter of which are received at the outer ends by a bracket 49 and attached to the frame end B near their inner ends, said frame being open to permit the ways to come partially within the frame ends. Dimensionally adjustable in the crank 50 of the intermittent gear 5, a crank pin 51 is fitted. This pin receives a pitman 52 which leads to, and is pivotally attached to, the cross head 47 by a pin 53 through which re- 120 125 130

ciprocal motion is imparted to the twisters 35 from the rack 46. The object of adjustably fitting the crank pin 51 is for the purpose of varying the reciprocal motion of the twister rack that moves the twisters to accommodate the varying widths between the cross stays of a fence, lengthening the throw of a crank to move the rack further increasing the revolutions of the twisters, and 10 shortening the throw of the crank decreasing the rotation of the twisters.

Motion is imparted to the sway-bar 18 from the wheel 3 by means of a pitman 54 pivoted to the bar by pin 55, and the connection of the pitman with the wheel is made from a crank pin 56 located on the toothed side of the wheel intermediate of the teeth and between the teeth and hub thereof, as shown.

20 Journaled in the base of the machine and near the end B is a rock shaft 57 carrying two upwardly-disposed diverging arms or levers 58 and 59, the lever 58 diverging toward the connection of the pitman 54 with the sway-bar 18. This lever is connected with the sway-bar and pitman 54 by a short pitman 60 journaled at one end to the pin 55 and at its opposite end to said lever by a pin 61. The arm or lever 59 carries an ext- 25 tension 62 made adjustable by means of a clamping bolt or other equivalent 63, and at its free end is provided with a slot 64. This lever is connected with a crimping wheel rack 65 by a pitman 66 attached to said rack 30 by a pin 67 from a depending portion thereof, and to said lever by a pin 68 through the slot 64, as shown in Figs. 1, 3 and 4. The object in making the arm 59 extensibly adjustable is for the purpose of increasing or 35 diminishing the throw of the pitman that actuates the crimping wheel rack to vary the rotation of the crimping wheels, (hereinafter more fully set forth), and thus shorten or lengthen the cross-bars or stays in accordance with the width of fencing to be 40 built.

The crimping wheel rack 65 lies parallel with the twister rack 46 and, as shown, is arranged to slide in bearings through the 45 ends A and B, although any suitably devised bearings could be arranged within the machine for this purpose.

Designated as the rearward side of the machine, a bracket 69 is fitted between the 50 twister rack 46 and the crimping wheel rack

65. Within the lower end of this bracket one end of the geared crimping wheel shaft 70 is journaled, its opposite end being journaled in a bracket 71 of the frame end A, as 60 shown in Fig. 2, and between these brackets the rack 65 engages a small spur gear 72 on the shaft 70 and operates the crimping wheels 73 and 74. The wheel 73 is loose on the shaft 70 and bears against the bracket 69, and the hub on the opposite side forms

a clutch engaging with a clutch 75 splined on the shaft 70 and longitudinally held in contact with the clutch of said wheel by a spring 76 adjustably held in position by a collar 77 on said shaft. The upper crimping wheel 74 is adjustable to and from the wheel 73 by means of an inverted L-shaped lever 78 pivoted near the upper end of the bracket 63 and adjustable thereon by means of a bolt 79 passing through a slot 80 in the lower arm thereof, as shown in Fig. 5. An extension 81 or fixture of the bracket 69 holds a guide pipe 82 in alinement with the pass between the crimping wheels through which pipe the wire 83 is fed to the crimping wheels to form cross-stays for the fence. The arrangement of the clutch 75 is such that the rack 65 will cause the crimping wheel 73 to feed the wire 83 into the machine at a predetermined time in the operation thereof, but permit said wheel to remain idle during a reverse operation of said rack.

A rock shaft 84 is journaled in suitable bearings above, and crosswise of the shafts 1 and 2, and at or near either end is fitted with cranks 85 and 86 and an intermediate crank 87, the two latter being arranged to oscillate said shaft by the rotation of the wheels 3 and H. The crank 87 is fitted with a friction roller 88 at one end thereof, and is adapted to bear against a race on the inner face of the wheel H, the race 88' being raised above the face of the wheel a portion of its distance to cause the crank 87 to oscillate in one direction, a pin 90 on the inner side of the wheel 3 actuating the crank 86 to oscillate the rock shaft in a reverse direction and at predetermined times. The crank 85 carries a pitman 91 that leads to and is pivoted at its opposite end to a vertically-disposed lever 92 pivoted at its lower end to a bracket 31, the latter of which is fitted with spaced steel bearings 93 above the pivotal connection with said lever and on either side of an aperture 94 of said bracket. The aperture 94 is in alinement with a corresponding aperture, (not shown), in the frame end A and in alinement with the stay wire 83 fed from the crimping wheels 73 and 74, and the arrangement of the lever 92 is such that a pair of shears is formed by which the stay wire is severed at predetermined times in the operation of the machine.

Pivoted on a stud 95 extending from the end frame A, a vertically-disposed rocker-lever 96 is journaled. This lever above its pivotal connection with said frame is connected with the shear lever 92 by a connecting rod 97 and at its lower end is connected with a depending crank 98 fixed on the rock shaft 30 by a short connecting rod 99.

The timing of the machine is such that as the lever 92 is advanced to sever a cross

130

stay through the connective parts, as described, the rock-shaft, 30, will raise the cross-bar guides 99, and force said bar firmly between the twisted strands of the fence immediately after the twistlers have completed twisting the strands between adjacent cross bars, as will be shown antecedent and subsequent to said operation in Figs. 3 and 4. In a normal position the rock shaft, 30, is positioned so that the cross bar guides, 99, rest upon the tops of the twistlers, as shown in Fig. 3, and the twistlers antecedent to thrusting a cross bar between the strands of the fencing are positioned so that the strands will stride said bar or, in other words, the machine is timed so that the twistlers are momentarily idle in this position when a cross bar is being thrust between the strands, such position being shown in Figs. 1, 2 and 3. The guides are longitudinally channeled with open tops, 100, and are bell-shaped toward the crimping wheels aforesaid, for the purpose of more readily receiving and guiding the cross bars over the twistlers. By preference the outer end of a bracket to which the cross bar guide is attached, is formed with a slot 101, extending from the end thereof, and encompasses the wire holes of the twister, as shown in Fig. 8.

Preparatory to operating, fencing strand wires α , and the cross bar or stay wire 83 are led to the machine from spools located below, the strands passing through tension holders (not shown). Each set forming a cable is first passed upward through a twister 35, thence up and between the crimping roll I and measuring and crimping roll J, and made fast to the fence winding reel K, and the cross bar or stay wire 83 is passed through the curved guide pipe 82 and between the crimping wheels 73 and 74.

In operation, as the wheel 3 revolves toward the right, the pitman 54 connected therewith through the pin 56 will operate the sway-bar 18 and through the medium of the lever hereinbefore described operate the crimping and measuring rolls I and J, the fencing reel K and the rack 65 operating the cross bar crimping wheels 73 and 74. The fencing reel and the measuring and crimping rolls are actuated to take up the fence at a time that the cable twistlers 35 are rotated, and this takes place when the pitman 54 is on its upward movement and the intermittent wheel 5 is in motion; this movement carries the pitman 52 and operates the cross head 47 and twister rack 46, said rack alternating the movement of the twistlers at each revolution of the intermittent wheel. During the time the twistlers 35 are idle, the rock shaft 84 is moved by the crank 87 through the medium of the raised portion of the race 88 on the gear H, and through the medium of the crank 85, the pitman 91 and

lever 92, the crimped cross bar is severed from the wire 83 and at the same time forced by the guides 99 upwardly between the twisted strands of the cables in the manner hereinbefore set forth.

Having, therefore, described my invention, what I claim as new and desire to secure by Letters Patent, is:

1. In a fence machine, the combination of a series of cross-bar guides having longitudinal, alined passages funnel-shaped at one end and open at the top, a rock shaft, brackets, adjustably mounted on said shaft to which said guides are attached, and means to rock said shaft.

2. In a fence machine, the combination of a series of cross-bar guides having longitudinally-alined passages funnel-shaped at one end and open at the top, a rock shaft, brackets adjustably mounted on said shaft supporting said guides, said brackets being slotted at their outer ends at one side of and adjacent to the passages through said guides, and means to rock said shaft and its guides, substantially as set forth.

3. In a fence machine, the combination with a supporting frame, of a bracket carried by said frame, intermeshing crimping wheels journaled one above the other on said bracket, means to adjustably regulate one of said wheels, a wire-feeding guide-pipe leading between said wheels, and means to intermittently actuate said wheels in one direction to draw a wire therebetween.

4. In a fence machine, in combination, a series of twistlers, cross-bar guides journaled to rest on said twistlers, a pair of shears located in alinement with said cross-bar guides, means to thrust a cross bar between the blades of said shears and through said guides between the wires of said twistlers, means to reciprocate said twistlers, means to actuate said shears and sever said cross bar, and means to actuate said cross-bar guides and force said cross bar firmly between the twisted strands of said wires antecedent to reciprocating said twistlers and subsequent to the closing of said shears.

5. In a fence machine, the combination with a series of twistlers and means to reciprocate the same, of a rock shaft, brackets adjustably mounted on said shaft and adapted to rest at their free ends on said twistlers, cross-bar guides having longitudinally-alined passages funnel-shaped at one end and open at the top carried to one side and at the free end of said brackets, means to thrust a crossbar through said guides and between the wires of said twistlers subsequent to the operation of said twistlers, and means to rock said shaft, its brackets and guides, and force said cross bar firmly between the twisted strands of said wires antecedent to reciprocating said twistlers.

6. In a fence machine, the combination

with the frame thereof, of two parallel transverse shafts journaled thereon, the one having a driving gear and a secondary gear at opposite ends thereof, the other having an 5 intermittent gear operative by said secondary gear and arranged to run one revolution to each two revolutions of the driving gear, a crank on said intermittent gear, twisters, a rack engaging said twisters, ways, 10 a cross-head in said ways, and a pitman connecting said crank with said cross-head, said crank being adjustably fitted to said intermittent gear whereby said rack movement may be lengthened or shortened, as 15 and for the purpose set forth.

7. In a fence machine, the combination with the frame thereof, of twisters operated therein, a fence-measuring roll and a fence-crimping roll journaled in said frame above 20 and in alinement with said twisters, a fence reel journaled in said frame to one side of and parallel with said rolls, means to simultaneously actuate and control said measuring roll, crimping roll and fencing reel, 25 means to prevent the recoil of said measuring roll, means to compensate for the variation of speed between the driving gear and the fencing reel occasioned from the increase in the bulk of fencing wound on said reel, 30 and means to simultaneously actuate said twisters, fence-measuring roll, fence-crimping roll, and fence reel.

8. In a fence machine, the combination of a series of twisters having reduced center 35 portions and enlarged bearings, one end thereof comprising a gear with a hub having an enlarged end provided with oppositely-disposed grooves, the opposite end being reduced, a supporting bar, brackets 40 mounted upon said bar, said twister bearings journaled within said brackets, set-screws in said brackets passing through and engaging said bar to adjustably secure said brackets, thimbles having holes in the end 45 thereof fitted over the reduced end-portion of said twisters and bearing against said brackets, longitudinal holes through said gears, bearings, and reduced end portion of said twisters in alinement with the holes in 50 said thimbles and the grooves in the enlarged portion of said hubs, for the passage of wires to be twisted.

9. In a fence machine, the combination of a series of twisters having reduced center 55 portions and enlarged bearings, one end thereof comprising a gear with a hub having an enlarged end provided with oppositely-disposed grooves, the opposite end being reduced, a supporting bar, brackets adjustably 60 mounted upon said bar, said twister bearings journaled within said brackets, thimbles having holes in the end thereof fitted over the reduced end portion of said twisters, a ring fitted between each of said thimbles 65 and said brackets, longitudinal holes through

said gears, bearings and reduced end portion of said twisters in alinement with the holes in said thimbles and the grooves in the enlarged portion of said hubs for the passage of wires that are to be twisted. 70

10. In a fence machine, the combination of a series of twisters having reduced center portions and enlarged bearings, one end thereof comprising a gear larger than its bearing and having a hub with an enlarged 75 end provided with oppositely-disposed grooves, the opposite end being reduced, a supporting bar, brackets slidably adjustable mounted on said bar, a rack engaging the gears of said twisters reciprocatively mounted in said brackets, means to reciprocate said rack, thimbles having holes in one end thereof fitted over the reduced end portion of said twisters and bearing against said brackets, longitudinal holes through said 80 gears, bearings, and reduced end portion of said twisters in alinement with the holes in said thimbles and the grooves in the enlarged portion of said hubs for the passage of wires that are to be twisted, substantially 85 as set forth.

11. In a fence machine, the combination with a supporting frame, of brackets carried by said frame, a geared shaft journaled on said brackets, a rack in engagement with 95 said gear, a feed and crimping wheel loosely journaled on said shaft, a ratchet longitudinally splined on said shaft in engagement with a corresponding ratchet on said wheel whereby said wheel will operate in one direction only, a spring impinging said ratchet on said shaft, means to adjust said spring on said shaft, an arm carrying a secondary feed and crimping wheel in engagement with said first-mentioned wheel pivoted to 100 said bracket, said arm having a slot, a stud projecting through said slot from said bracket, a nut run on the threaded end of said stud whereby said arm may be adjusted to swing said secondary wheel to or 105 from said first-mentioned wheel, a wire-feeding guide-pipe leading between said wheels, and means to reciprocate said rack. 110

12. In a fence machine, the combination with the frame thereof, of a series of 115 twisters, a rack to reciprocate said twisters, guides for said rack, a pitman pivoted to said rack, a crank to actuate said pitman, means to regulate the throw of said crank whereby the motion of said twisters 120 may be increased or diminished in rotation to vary the twist of the wires in the strands of the fence in the spacing of cross bars, cross-bar guides alined above said twisters, cross-bar feed and crimping wheels arranged in alinement with said cross-bar guides to feed cross-bar wire to said guides, 125 a rack to actuate said feed and crimping wheels, a pitman to actuate said rack, a rock lever to actuate said pitman, means 130

to adjust said lever whereby the thrust of said pitman and the movement of said rack may be varied to accommodate varying lengths of cross bars through said guides, means to actuate said rock lever, means to intermittently actuate said twister-operating mechanism whereby said cross-bar feed and crimping wheels will thrust a cross bar through said cross-bar guides subsequent to their rotation, and means to sever said cross bar subsequent to the thrust of said cross bar through said guides.

13. In a fence machine, the combination of twisters, a measuring and a crimping roll arranged in alinement with and above said twisters, a fence reel arranged parallel with said measuring and crimping rolls, cross-bar guides arranged in alinement with the tops of said twisters, cross-bar crimping wheels arranged to feed wire into said cross-bar guides, shears arranged in the path of said cross-bar wire between said crimping wheels and between said cross-bar guides, means to reciprocate said twisters simultaneously with means to actuate said measuring roll, crimping roll, and fencing reel to draw the fencing from said twisters, means to actuate said crimping wheels to thrust a cross bar through the cross-bar guides subsequent to the operation of said twisters, and means to actuate said shears and sever said cross bar subsequent to means for thrusting said cross bar through said cross-bar guides, and simultaneously with means to lift said cross-bar guides and force said cross bar firmly between the twisted strands of the fence.

14. In a fence machine, the combination with the frame thereof, of two parallel transverse shafts journaled thereon, the one having a driving gear at one end and a secondary gear at the opposite end, the other having an intermittent gear operative from said secondary gear and arranged to revolve once to two revolutions of the secondary gear, a crank on said intermittent gear, twisters, a rack engaging said twisters, ways, a cross head operating in said ways, a pitman connecting said crank with said cross head, a fencing reel, measuring roll and crimping roll journaled in said frame and transverse of said shafts, said measuring roll and crimping roll being alined above said twisters, and said fencing reel being arranged parallel with and at one side of said twisters, means to simultaneously actuate said reel and rolls, crimping wheels, a gear on a shaft of one of said wheels arranged to roll said wheels toward said machine, a rack engaging said gear, cross-stay guides resting on said twisters, shears arranged in the path between said crimping wheels the tops of said twisters and said cross stay guides, a sway bar pivoted at one

end beneath and transverse of said parallel shafts, a crank on said secondary gear, a pitman connecting said crank with said sway bar, a ratchet on said take-up roll, a lever engaging the shaft of said roll, a pawl on said lever engaging said ratchet, a pitman connecting the free end of said sway bar with the lever having said pawl, means to reciprocate the rack arranged to operate said crimping rolls from said secondary gear, means to operate said shears, and means to actuate said cross-bar guides to coact in the manner as and for the purpose set forth.

15. In a fence machine, the combination with the frame thereof, of two parallel transverse shafts journaled therein, a driving gear on the end of one shaft and a secondary gear on the opposite end, an intermittent gear on the opposite shaft engaging with said secondary gear and arranged to revolve one-half revolution to one complete revolution of the driving gear, a crank on the intermittent gear, ways on said machine, a cross head in said ways, a rack engaging said cross head, a pitman connecting said crank with said cross head, wire twisters operated by said rack, a crank on said secondary gear, a sway bar pivoted below said parallel shafts and transverse thereto, a pitman connecting said sway bar with the crank of the secondary gear, geared measuring and crimping rolls, and a fence winding reel journaled on said frame parallel with said twisters, the two former being alined above said twisters, means to simultaneously actuate said rolls and reel, a ratchet on one of said rolls, a lever journaled on the ratcheted roll, a pawl carried by said lever engaging said ratchet, a connecting rod engaging the lever of said pawl with the outer end of said sway bar, a rock shaft journaled below and transverse of said sway bar, diverging arms on said shaft, a pitman connected at one end to the free end of one arm and at the opposite end to said sway bar, a geared shaft, a rack engaging said gear, a pitman pivoted at one end to said rack and at the opposite end to the other of said diverging arms, a ratchet longitudinally splined on said geared shaft, a crimping wheel having a ratchet in engagement with said splined ratchet but loose upon said shaft, a spring engaging said splined ratchet to hold said ratchets in engagement, a secondary crimping wheel journaled above said ratchet wheel, a cross-bar feed pipe alined between said crimping wheels, a rock shaft, cross-bar guides alined on said shaft and resting upon said twisters and in alinement with said feed pipe, a rock shaft transverse of said parallel shafts, cranks on said shaft, means to oscillate said shaft from said drive-gear shaft, a pair of

shears opening between the path of said cross-bar feed pipe and said cross-bar guides, a pitman connecting one of said cranks of said last-named rock shaft with a pivoted arm of said shears, and means connected with the pivoted arm of said shears to lift said cross-bar guides when said shears

are closed and to react the same when said shears are opened, all arranged to act substantially as and for the purpose set forth.

GEORGE A. RAYMOND.
